CLAIM

The ornamental design for a crate, as shown and described.

DESCRIPTION

FIG. 1 is a top, front, right side perspective view of a first embodiment of the crate of the new design.

FIG. 2 is a bottom, rear, left side perspective view of the crate of FIG. 1.

FIG. 3 is a front elevation view thereof, the rear elevation view being an identical image of the front elevation view. FIG. 4 is a left side elevation view thereof, the right side elevation view being an identical image of the left side elevation view.

FIG. 5 is a top plan view thereof.

FIG. 6 is a bottom plan view thereof.

FIG. 7 is a top, front, right side perspective view of a second embodiment of the crate of the new design.

FIG. 8 is a bottom, rear, right side perspective view of the crate in FIG. 7.

FIG. 9 is a front elevation view thereof, the rear elevation view being an identical image of the front elevation view.

FIG. 10 is a left side elevation view thereof, the right side elevation view being an identical image of the left side elevation view.

FIG. 11 is a top plan view thereof; and,

FIG. 12 is a bottom plan view thereof.

The broken lines showing is included for the purpose of illustrating environment and forms no part of the claimed design.

1 Claim, 12 Drawing Sheets
